(57) **CLAIM**

The ornamental design for a boat shaped key chain, as shown and described.

DESCRIPTION

FIG. 1 is a perspective view of a boat shaped key chain; and
FIG. 2 is a top view of the boat shaped key chain;
FIG. 3 is a bottom view of the boat shaped key chain;
FIG. 4 is a front view of the boat shaped key chain;
FIG. 5 is a rear view of the boat shaped key chain; and,
FIG. 6 is a right hand side view of the boat shaped key chain.
The broken lines showing a key in FIGS. 1 to 5 are included
only for the purpose of illustrating an environment and form
not part of the claimed design.
